F. H. CORDIS.

SPARK ARRESTER FOR RAILROAD LOCOMOTIVES.

FILED MAR. 11, 1922.

Patented Feb. 6, 1923.

1,444,306

UNITED STATES PATENT OFFICE.

FRED HENRY CORDIS, OF THEDFORD, NEBRASKA.

SPARK ARRESTER FOR RAILROAD LOCOMOTIVES.

Application filed March 11, 1922. Serial No. 542,850.

To all whom it may concern:

Be it known that I, FRED HENRY CORDIS, a citizen of the United States, and a resident of Thedford, in the county of Thomas and 5 State of Nebraska, have invented certain new and useful Improvements in Spark Arresters for Railroad Locomotives, of which the following is a specification.

This invention relates to a spark arrester 10 for railroad locomotives or the like.

The object of the invention is to provide a spark arrester which may be attached to the smoke stack of a locomotive in an easy manner and which will thoroughly serve for arresting sparks issuing from the associated smoke stack and thus to prevent the possibility of a fire being started by the said sparks.

It is also an important object of the invention 20 that the spark arrester be adapted to in no way interfere with the normal operation of the locomotive.

It is a further object of the invention that the arrester be so constructed that it may 25 be swung from its operative position with relation to a smoke stack in an easy manner and thus to permit sparks to freely pass from the smoke stack when so desired.

It is a further object of the invention that 30 the apparatus be extremely simple in construction and inexpensive to manufacture.

Other objects and advantages relating to 35 details of construction, combination and arrangement of parts will hereinafter appear in the detailed description to follow.

The invention is illustrated by way of example in the accompanying drawings, in which,

Figure 1 is a perspective view illustrating 40 the front portion of the body of the locomotive and showing the arrester of the present invention applied to the smoke stack of said locomotive.

Figure 2 is a vertical sectional view of the 45 arrester and showing a portion of the smoke stack to which the arrester is applied.

Figure 3 is a transverse sectional view taken substantially on the line 3—3 of Figure 2.

50 Referring to the drawings more particularly B indicates generally the body structure of a steam locomotive and S the smoke stack associated therewith which is of the usual construction.

55 In carrying out the present invention there is provided a pair of clamp members

10, said clamp members being complementary and adapted to be fitted about the smoke stack S and each clamp member having its ends terminating in an outwardly extending 60 portion 11. Between the pairs of extensions 11 occurring at opposing ends of the clamp members 10 there is positioned in each instance a bolt 12 whereby the clamp members may be secured about the smoke stack S. 65 Also each clamp member may be provided with an inner lining of asbestos or the like as at 13. Each member 10 has extending outwardly therefrom a pair of tangs 14 through which there is extended in each instance the threaded end of a bolt 15. Each bolt 15 terminates at its upper end in a hook 16 which is adapted to engage upon the upper portion of the stack S as shown in Figures 1 and 2. The threaded or lower end of 70 each bolt 15 carries a nut 17 whereby the clamp members 10 may be adjustably raised or lowered. Each member 10 is also formed with a pair of apertured ears 17', the purpose of which will later appear. The members 10 serve to support the spark arrester which will presently be described and may be easily attached or detached from the stack S.

The spark arrester proper comprises a 85 cover generally indicated by the reference numeral 18 which is formed about its edge with a downwardly curved lip 19. The cover or top 18 has formed therewith the forward and rearward supporting legs 20 90 and 21, respectively, and also the pair of side supporting legs 22. The lower end of each supporting leg terminates in a sleeve 24. The lower end of each leg 20 and 21 is disposed between the associated pair of extensions 11 of the clamp members 10 and journaled therebetween by a bolt 25. The bolt associated with the leg 21 is provided with a nut 26 for holding the same against displacement while the bolt associated with 95 the leg 20 is provided with a cotter pin 27 for a similar purpose. The sleeve 24 of each side leg 22 is disposed between the associated pair of ears 17' of the clamp members 10 and supported in this position by a 100 bolt 27, said bolt in each instance extending through the pair of ears 17 and also through the sleeve 24 as shown. The cover or top 18 supports an inverted conical shaped casing generally indicated by 110 the reference numeral 29, said casing having its base portion formed with a plurality of

tangs 30 which are extended through suitable recesses or openings in the cover 18 and then bent over in order to sustain the casing 29 in position. Also for holding the casing 29 against displacement there is provided a rod 31, said rod extending centrally through the casing 29 and having its lower end formed with a head 32 adapted to limit the upward movement of the rod. The upper end of the rod extends through a suitable opening in the cover 18 and is provided with a nut 33 by which the casing 29 may be drawn against the cover 18.

In applying the present arrester to a smoke stack of a locomotive, the clamp members 10 should, of course, be first positioned. If desired the cap or cover 18 together with the conical casing 29 and associated parts may be removed in order to expedite the securing of the members 10. The bolts 15 should have their hook portions 16 engaged upon the upper edge of the spark and the members 10 clamped in position by the bolts 12. The cover 18 together with parts connected therewith including the conical casing 29 may now be positioned upon the members 10. The pointed end of the casing 29 will extend within the stack S and the distance this end extends may be adjusted by the means of the bolts 15. If it is desired to remove the arrester from the smoke stack, that is, remove the cap or cover 18 and casing 29 from the operating position then the cotter pin 27 may be removed and the bolt 25 taken out and also the bolts 27 which secure the side legs 22. The cover 18 and attached casing 29 may now be swung rearwardly upon the journal of the rear leg 21 as a pivot.

When the arrester is positioned as illustrated in the different figures of the drawings its operation is as follows: The sparks issuing from the stack S will be deflected outwardly by the conical casing 29 and when proceeding upwardly will impinge upon or collide with the lip 19 of the cover 18. The lip 19 is so arranged that the sparks when colliding therewith and falling down will fall upon the outside of the stack S and thus insuring that these sparks will not collect within the stack and interfere with the normal operation of the locomotive. This is an important feature of the invention and is thought to be clearly apparent without further elaboration.

While I have herein shown and described only one form of spark arrester embodying my invention, it is to be understood that various changes and modifications may be made herein without departing from the spirit of the invention or the spirit and scope of the appended claims.

What I claim is:

1. A spark arrester of the character described comprising a cap consisting in a

flat central portion formed about its edge with a downwardly curved lip, an inverted conical shaped member supported by said cap, the base portion of which is substantially equal in diameter to the central portion of said cap, and means whereby said conical shaped member and cap may be supported over a smoke stack so that the pointed end of said conical shaped member is disposed a predetermined distance within the upper end of the smoke stack.

2. A spark arrester of the character described comprising a cover with a downwardly curved lip formed about the edge thereof, a plurality of legs extending downwardly from said lip, means whereby said legs may be secured to the smoke stack for supporting the cover a predetermined distance above the smoke stack, and an inverted conical shaped casing supported by said cap and with its pointed end projecting a predetermined distance within the associated smoke stack.

3. A spark arrester of the character described comprising a cover with a downwardly curved lip formed about the edge thereof, a plurality of legs extending downwardly from said lip, means whereby said legs may be detachably connected to a smoke stack, means whereby the legs may be adjustably moved upward or downward with respect to said smoke stack to adjust the distance between the cap and upper end of the smoke stack, and a conical shaped inverted casing supported by the cap and with its pointed end extending a predetermined distance within the upper end of the stack, and the lip portion of said cap extending from the base portion of said conical shaped member.

4. A spark arrester of the character described comprising a cover consisting in a circular plate-like portion having a downwardly curved lip formed upon the periphery thereof, a pair of legs extending downwardly from said lip, a pair of semi-circular clamp members adapted to encircle a smoke stack, each clamp member being formed at its ends with an extension whereby to provide means for pivotally supporting the pair of legs extending downwardly from said cap, means whereby said clamp members may be secured to a smoke stack for adjustably raising and lowering the same, and an inverted conical shaped member supported by said cap and its pointed end extending a predetermined distance within the upper end of the associated smoke stack.

5. In combination with a smoke stack of a locomotive, a pair of semi-circular clamp members adapted to be positioned upon the smoke stack of the locomotive, said clamp members having lateral extensions at each of its ends, bolts extended through said ex-

tensions for securing said clamping members in position, and a spark arrester having a pair of downwardly extending supporting members secured between said extensions of 5 the clamping members.

6. In combination with a smoke stack of a locomotive, a pair of semi-circular clamp members adapted to be positioned upon the smoke stack of the locomotive, said clamp 10 members having lateral extensions at each of its ends, bolts extended through said extensions for securing said clamping members in position, a spark arrester having a pair of downwardly extending supporting members 15 secured between said extensions of the clamping members, a second pair of supporting members for said spark arrester, and means extending from each of the clamp members to which the last named supporting members for the spark arrester may 20 be secured.

7. In combination with a smoke stack of a locomotive, a pair of semi-circular clamp members adapted to be positioned upon the 25 smoke stack of the locomotive, said clamp members having lateral extensions at each of its ends, bolts extended through said extensions for securing said clamping members in position, a spark arrester having a 30 pair of downwardly extending supporting members secured between said extensions of

the clamping members, a second pair of supporting members for said spark arrester, means extending from each of the clamp members to which the last named supporting members for the spark arrester may be 35 secured, and a plurality of bolts for each of the clamp members, each of said bolts having its lower end adjustably connected to the associated clamping member and its upper end formed with a hook adapted to engage the rim of the smoke stack for further supporting the spark arrester.

8. In combination with the smoke-stack of a locomotive, a pair of clamp members, 45 each semi-circular in shape and adapted to be fitted or positioned upon the smoke stack and said clamp members having their ends formed with lateral projections, bolts extending between similar lateral projections 50 of said clamping members whereby the same may be drawn together, a spark arrester positioned above the smoke stack and having a pair of downwardly extending supporting legs pivotally connected between the extensions of said clamping members, said pivot connection of one of the supporting members being detachable to permit the spark arrester to be swung upon its other support.

FRED HENRY CORDIS.
